UNITED STATES PATENT OFFICE.

LEWIS R. HEIM, OF DANBURY, CONNECTICUT, ASSIGNOR TO FERNANDO C. OLMSTEAD, OF DANBURY, CONNECTICUT.

HAT-CURLING MACHINE.

SPECIFICATION forming part of Letters Patent No. 695,393, dated March 11, 1902.

Application filed August 26, 1901. Serial No. 73,290. (No model.)

To all whom it may concern:

Be it known that I, LEWIS R. HEIM, a citizen of the United States, residing at Danbury, in the county of Fairfield and State of Connecticut, have invented certain new and useful Improvements in Hat-Curling Machines; and I do hereby declare the following to be a full, clear, and exact description of the invention, such as will enable others skilled in the art to

10 which it appertains to make and use the same.

My invention relates to certain new and useful improvements in hat-curling machines, and has for its objects to properly deliver the hat-brim to the curling instrumentalities, 15 while at the same time the under side of the brim shall not be marred in any way, to effect the proper curl in all instances with the fewest possible adjustments of the curling devices, to obviate the necessity of swinging 20 the initial curling devices outside the normal horizontal plane in which they operate, to prevent the curling devices from marring the crown of the hat when said devices are separated to release the curled brim, to relieve 25 the convex curling wheel or roll of any function other than the actual curling operation, and finally to provide a machine which shall be exceedingly simple and positive in its operation.

30 With these ends in view my invention consists in certain details of construction and combination of parts, such as will be herein-after fully set forth and then specifically be designated by the claims.

35 In the accompanying drawings, which form a part of this application, Figure 1 is a side elevation of my improved curling-machine; Fig. 2, a front elevation; Fig. 3, a plan view; Fig. 4, a section at the line $x-x$ of Fig. 3; and 40 Figs. 5, 6, and 7 are respectively a plan, a front elevation, and a side elevation, of the curling-shackle.

Similar numbers of reference denote like parts in the several figures of the drawings.

45 Heretofore hat-curling machines have been used which employed a small wheel or roll having a convex surface in connection with a large wheel having a concave periphery, these two rolls or wheels constituting the 50 curling devices between which the hat-brim was initially delivered. Also such machines

employed devices located beyond the initial curlers, which devices perfected and finally "set" the curl substantially in the manner shown in the drawings of the present application; but in these prior machines the large roll or wheel having the concave periphery has afforded no support or guide whatsoever for the hat-brim at the under side, since the smallest diameter of this wheel is at the bottom—that is to say, its periphery in cross-section is only about one-quarter of a circle. Also in the prior machines of this sort no provision has been made to shield the brim of the hat, so that it would not strike against the top edge of the large curling wheel or disk before such brim was engaged by the curling instrumentalities, and consequently the under side of the brim was frequently marred. Furthermore, in these prior machines 70 the spindle which carried the smaller or convex curling-button was so arranged as to be withdrawn from the large wheel or disk in order that after curling the hat might be removed, but unless great care was exercised on the part of the operator the crown of the hat would be scraped against this shaft, because the latter was thus brought very close to said crown.

My invention aims to obviate the above-noted disadvantages and will be best understood from the following description.

1 is the bed of the machine, from which rises a standard 2, to which latter is secured a bracket 3.

4 is the primary shaft, journaled in suitable bearings 5 6, carried by the bracket, said shaft having on its inner end a worm 7 and on its outer end the usual power-pulleys 8 9.

10 is a vertical shaft journaled in a bearing 90 11 on the bracket 3, said shaft carrying a worm-wheel 12, which engages with the worm 7.

13 is a spur-gear, also carried by the shaft 10, near the lower end, and at the extreme lower end of said shaft is secured the curling-button 14, which has a convex periphery.

15 is a bracket, one end of which is pivoted loosely around a vertical spindle 16, secured to the bed 1, the upper part of said spindle being threaded and provided with a nut 17, while a coil-spring 18 is confined between said nut and bracket, so that it will be

clear that said bracket may be moved upwardly against the resiliency of the spring. Within the other or free end of this bracket 15 is secured a vertical spindle 19. Loosely arranged around this spindle are the large curling-wheels 20 21, the former of which is provided with a hub 22, which rests upon the bracket 15 and is loose around the spindle 19, while the wheel 21 has a hub 23, which is tight on the hub 22, so that said wheels will be capable of revolution in harmony. The wheel 21 is hollowed out, as shown at 24, and both wheels are perforated, as shown at 25 26, for the purpose presently to be explained. 15 These two wheels 20 21 are of the same diameter and have concave peripheries 27 28, respectively, these concave portions forming a semicircle when the wheels are assembled for operation, as shown in the drawings. 20 Rigidly secured to the hub 22 on the wheel 20 is a spur-gear 29, which meshes with the spur-gear 13, but of considerably larger diameter than the latter.

The convex surface of the button 14 corresponds to the concave peripheral surface 27 of the upper wheel 20, and the normal position of said button with respect to said wheel is such that the peripheries of said button and wheel are separated by a predetermined 30 space sufficient to admit the thinnest hat-brim, and when a thicker hat-brim is passed between said button and wheel the latter will slightly raise upwardly against the resiliency of the spring 18, so as to readily admit such 35 brim and exert a proper pressure thereon.

From the foregoing description it will be readily understood that if a hat-brim be passed between said button and the wheel 20 it will be curled around the convex surface 40 of said button and there will be no drag on the hat-brim, owing to the fact that said button and wheel are revolving at proper speeds, which are of course determined by the relative sizes of the gears 13 and 29.

45 30 is a table which is secured in any suitable manner (not shown) to the bed 1 and which is substantially in the same horizontal plane with the bottom of the lower curling-wheel 21, and in the operation of curling the 50 hat-brims the brims of the hats are placed upon this table and moved forward until they are engaged between the wheel 20 and button 14.

55 31 is a ledge which extends laterally from the upper part of the bracket 15, and 32 is a plate which is rigid with the male curling-shackle 33, which plate is secured upon this ledge.

34 is the female member of the curling-60 shackle, which is secured by means of screws 35 to the male member of the shackle, so as to leave a suitable space 36 between these male and female members in the usual manner provided in curling-shackles, the lower-65 most portion of the male shackle extending below the lowermost portion of the female

shackle a distance equal to the thickness of a hat-brim.

37 is the mouth of the male shackle, which is flaring and opens downwardly and has no 70 floor or bottom portion whatever. The normal position of the curling-shackle, composed of its male and female members, is such that the flaring mouth 37 will be a continuation of the concave surface of the peripheries of 75 the upper wheel 20, the outer edge of the flaring mouth 37 being very thin and its curvature corresponding to the concavity of the periphery of this upper wheel, so that a hat-brim initially curled between the button and 80 the wheel 20 will readily be delivered within the flaring mouth 37 of the curling-shackle.

The table 30 is flush with the lower edge of this flaring mouth 37, so that it will be clear that the hat-brim will meet with no obstructions in its delivery from the button 14 and wheel 20 to the curling-shackle, and in this connection I would state that it is of the greatest importance that the mouth 37 should have no lower portion or floor.

85 38 is a pipe secured in any suitable manner to the ledge 31, the inner side of said mouth being directed immediately against the concave periphery of the upper wheel 20. This pipe is for the purpose of heating the upper 95 wheel 20 and is used as the means for conducting any suitable gas or heating agent.

The lower wheel 21 is a very important feature of my invention in that it serves as a guide to assist in the proper delivery of the 100 hat-brim from the table between the button 14 and wheel 20, and the fact that this lower wheel 21 is not stationary, but revolves in 105 harmony with the upper wheel 20, is also a great advantage, in that there can be no drag on the hat, but it is important that the lower part of the hat-brim shall not become glazed by any heated surface, and therefore I have provided a fender 39, which is secured on top of the ledge 31 and which extends close to 110 the horizontal point of junction of the wheels 20 21, the inner mouth of the gas-pipe 38 being immediately above this fender, so that as the wheels 20 21 revolve the heat will be thrown against the upper wheel 20, but will 115 be shielded from the lower wheel 21 by means of the fender 39.

The lower wheel 21 is hollow, as seen at 24, and perforations 25 26 are made in the upper and lower wheels in order that there may be 120 a minimum metal body in the lower wheel for heat-conducting purposes and also for the purpose of creating an air-blast which may attack the greater interior area of the lower wheel, and thereby tend to keep the latter 125 cool.

In order that the brims of the hats may not strike against the upper edge of the wheel 20, so as to scratch or mar said brims, I have provided a shield 40, which is secured to the 130 table 30 and which extends immediately in front of the wheel 20 in close proximity to the

button 14, so that the hat-brims can never be touched on the under side by the revolving upper edge of said wheel 20.

41 is a coil-spring whose ends are secured, respectively, to the free end of the bracket 15 and to the table 30, the function of this coil-spring being to keep the wheels 20 21 normally in proper position with respect to the button 14.

10 42 is a bell-crank lever pivoted at its angle to a lug 43 rising from the bed 1, the upper leg of this bell-crank extending vertically athwart the outer surface of the bracket 15, while a suitable treadle (not shown) is connected to the extremity of the lower or horizontal leg of this bell-crank by means of an ordinary wire, chain, or cord 44.

After a hat has been completely curled the depression of the treadle will cause the upper 20 or vertical leg of the bell-crank to strike against the bracket 15, and thereby swing the same rearward, thus carrying the wheels 20 21 and the curling-shackle away from the button 14, so that the hat can then be readily 25 removed from the curling-shackle and button.

It will be clear that by moving the wheels 20 21 and the curling-shackle a far greater clearance will be left for the removal of the curled hat than would be the case if the shaft 30 of the curling-button were moved or tilted, because the tilting or moving of this curling-button shaft will bring the latter so close to the crown of the hat that the exercise of the greatest care will not prevent the scratching 35 of the crown by means of said shaft or button.

The provision of the curling-shackle so that the male member is provided with an integral flaring mouthpiece is an advantage in that it does away with two adjustments, 40 which would necessarily have to be made in case the mouthpiece were made separate from the shackle, and, as I said before, the utmost care must be taken in order that there should not be the slightest obstruction to the under 45 side of the hat-brim during its delivery to the curling devices.

After the hat has been delivered to the curling-shackle it will pass through the same, and there will be ample room left for the 50 brim of the hat beneath the shackle, since, as will be clear by reference to Figs. 1, 2, and 7, the lowermost part of the male member of the shackle extends below the bottom of the female member, so that the outer periphery 55 of the curled brim may strike against and be retained by the male member and at the same time the brim itself may lie flat on the table 30 beneath the female member.

Having thus described my invention, what 60 I claim as new, and desire to secure by Letters Patent, is—

1. In a hat-curling machine, the combination of a revoluble button, two revoluble disks having concave peripheries, means for revolving said disks and button, means for moving said disks toward and away from said button, and means for preventing heating of

one of said disks while the other is being heated, substantially as described.

2. In a hat-curling machine, the combination of the two disks journaled in a movable resilient bracket and having concave peripheries which are complementary parts of a semicircle, the revoluble button having a convex periphery and stationary except as to movements about its axis, means for heating the upper disk, means for deflecting the heat from the lower disk, means for imparting revolution to said button and disks, the curling-shackle carried by said bracket and arranged 75 in proximity to said button and disks, and means for moving said disks toward and away from said button, substantially as set forth.

3. In a hat-curling machine, the combination of the two separate disks capable of revolution upon a common axle and having concave peripheries which are complementary parts of a semicircle, means for heating one of said disks, means for deflecting the heating agent from the other of said disks, the 80 revoluble button having a convex periphery in close proximity to the heated disk, said button being stationary except as to movement around its axis, the curling-shackle having a flaring downwardly-opening mouth in proximity to said button and heated disk, means for revolving said button and disks, and means for moving said disks and curling-shackle toward and away from said button, 85 substantially as set forth.

4. In a curling-machine, the combination of the movable bracket, the divided disks having concave peripheries which are complementary parts of a semicircle and which are carried by said bracket, means for heating 90 one of said disks, means for deflecting the heating agent from the other of said disks, the revoluble button having a convex periphery in close proximity to the heated disk and stationary except as to movement about its 95 axis, a spring attached to said bracket on the frame of the machine whereby said disks are normally kept in proximity to said button, 100 means—as a lever operated by a treadle—whereby said disks are moved away from said button, the curling-shackle carried by said bracket and having a flaring downwardly-opening mouth in close proximity to said button and heated disk, and means for imparting revolution to said disks and button, substantially as set forth.

5. In a hat-curling machine, the combination of the frame, the bracket pivoted thereto and capable of an upward resilient movement, the divided disks journaled within the outer 110 end of said bracket and having concave peripheries which are complementary parts of a semicircle, the revoluble button in close proximity to one of said disks and having a convex periphery and stationary except as to movements about its axis, the curling-shackle carried by said bracket and having a flaring mouth opening downwardly and in close proximity to said disks and button, means for 115 120 125 130

- heating one of said disks, means for deflecting the heating agent from the other of said disks, and means for moving said bracket and the parts carried thereby toward and away from said button, substantially as set forth.
6. In a hat-curling machine, the combination of the divided disks having concave peripheries which are complementary parts of a semicircle, the revoluble button having a convex periphery in close proximity to said disks, the curling-shackle having a flaring downwardly-opening mouth in proximity to said button and disks, means for heating one of said disks, means for deflecting the heating agent from the other of said disks, and the shield extending in front of the heated disk adjacent to said button, substantially as set forth.
7. In a hat-curling machine, the combination of a pair of disks journaled in a movable bracket and having registering concave peripheries, a revoluble button having a convex periphery, means for rotating said button and disks, means for heating one of said disks during rotation, and means for preventing heating of the other of said disks, substantially as described.

8. In a hat-curling machine, the combination of a movable bracket, a pair of disks journaled therein and having concaved peripheries, a curling-button revolvably mounted near said disks, means for revolving said disks, means for heating one of said disks, and a fender near said heating means for preventing heating of the other of said disks, substantially as described.

9. In a hat-curling machine, the combination with a resilient bracket pivoted to swing in a horizontal plane, of a disk journaled therein, a button revolvably mounted near said disk, means for retaining said button against longitudinal or lateral movement, means for rotating said disk, and a curling-shackle carried by said bracket, arranged in proximity to said button and disk, and means for moving said shackle away from the button to free the hat curled, substantially as described.

In testimony whereof I affix my signature in presence of two witnesses.
